UNITED STATES PATENT OFFICE.

CHARLES F. SMITH, OF PITTSBURGH, PENNSYLVANIA.

CURRENT-REGULATOR.

1,367,631.

Specification of Letters Patent.

Patented Feb. 8, 1921.

Application filed April 12, 1920. Serial No. 373,162.

To all whom it may concern:

Be it known that I, CHARLES F. SMITH, a resident of Pittsburgh, in the county of Allegheny and State of Pennsylvania, have 5 invented a new and useful Improvement in Current-Regulators, of which the following is a specification.

This invention relates to electric current regulators, and has particularly to do with of 10 regulators for controlling the supply of electric current to the headlights of automobiles and like vehicles. The object is to provide a current regulator which will be simple in construction, effective in operation, and which may be economically manufactured.

The invention is illustrated in the accompanying drawings, of which Fig. 1 is a vertical sectional view through a portion of the 20 dash board of an automobile, the view showing the current regulator attached to the steering rod housing; Fig. 2 a face view of the regulator; Fig. 3 a sectional view taken on the line III—III, Fig. 2; Figs. 4 and 5 25 sectional views taken, respectively, on the lines IV—IV and V—V, Fig. 3; Fig. 6 a sectional view taken on the line VI—VI, Fig. 2; and Fig. 7 a view corresponding to Fig. 6, but showing a modification of construction.

In the embodiment of the invention illustrated in the drawings, the regulator mechanism is mounted within an elongate casing having sides 1, ends 1^a, a top 2 and a bottom 3, preferably constructed of sheet metal. The top, sides and ends may be pressed from a single sheet of metal, and the bottom may be made separately and secured to the sides, as by means of screw bolts 4. Within the 35 casing there are two plates 5 and 6 of insulating material which extend substantially from end to end of the casing and are connected to each other and to the top 2 of the casing by means of bolts 7. Between these 40 plates there is arranged a channel-shaped contact member 8 made of conducting material, the legs or flanges of such member acting as a spacer between the plates. On the plate 5 there is mounted a rheostat, the resistance element of which preferably consists of a coil 9, to which there are attached a plurality of contact buttons 10 extending through the mounting plate 5 and arranged 45 in longitudinal series. The contact button 50 10^a at the lower end of the series is attached to a binding post 11, to which a circuit wire

12 is connected. The other circuit wire 13 is connected, as by means of a binding post 14, to the contact member 8.

A movable contactor is mounted within 60 the casing to control the flow of current from one or another of the buttons 10 to the contact plate 8. Such movable contactor preferably comprises a conducting plate 15 arranged to slide between the legs of the channel 65 8 in continuous contact with the base of the channel. A portion of the contact or plate 15 is slit and bent downwardly to form a spring arm 16 adapted to bear yieldingly upon the top of the contact buttons 10. 70 By thus bearing upon the contact buttons, the spring arm 16 has the effect of yieldingly holding a movable contactor in contact with the rheostat buttons and the contact plate 8. 75

For moving the contact 15, it is preferably attached to a knob 17 by means of a screwed bolt 18 which extends through registering slots formed in the top 2 of the casing, the insulating plate 6, and the back of the contact plate 8. Preferably, the slot through the casing top 2 is enlarged to receive the lower end of the knob 17, as may be seen in Figs. 2 and 6. Through these registering slots and through openings 31 in the mounting plate 5, the coil 9 is vented to the atmosphere for cooling the coil. 85

To attach the regulator to the housing 20 of a steering rod, the sides 1 of the casing 90 may be extended below the bottom 3 and may be provided with straps 21 and lugs 22, the straps being adapted to engage the housing and to be clamped to the lugs by means of screw bolts 23. As an alternate form of construction, the bottom of the casing 95 may be made as indicated in Fig. 7. As there shown the bottom 3^a has straps 24 attached to it, which straps may be drawn together at both their inner and outer ends by means of screw bolts 25 and 26. The 100 provision of the two screw bolts for each pair of straps renders the straps suitable for attaching the regulator to various sized and shaped rod housings, and by providing bottoms 3^a with straps of different lengths, 105 say about three different sizes, the main body of the casing and its contained current-regulator mechanism may be the same for all sizes of steering rod housings.

The regulator may be conveniently attached to the upper end of the steering rod housing as indicated in Fig. 1, the knob 17 110

being in a very convenient position for movement by the driver. The conductors 12 and 13 may extend along the housing 20, through the dash-board 27, and be connected to a switch 28 mounted on the dash-board. When the knob 17 is at its lowermost position, that is to say the position most remote from the steering wheel 30, the full supply of current will flow through the conductor 12, binding post 11, contact button 10^a, arms 16, plate 15, channel 8, and binding post 14 to the conductor 13. By moving the knob 7 upwardly, the supply of current is reduced in proportion to the amount of the electric resistance coil thrown into the circuit. When the arm 16 is in contact with the upper button 10, the greatest resistance is thrown into the circuit, with the result that the smallest amount of current is supplied to the lamps. By using such a regulator, the headlight lamps may be of large candle power to afford bright illumination when desired, and the intensity of the illumination may be reduced to various amounts depending upon particular requirements.

According to the provisions of the Patent Statutes, I have described the principle and operation of my invention, together with the construction which I now consider to represent the best embodiment thereof. However, I desire to have it understood that, within the scope of the appended claims, my invention may be practised by other forms of construction than that particularly shown and described herein.

I claim:

1. A current regulator for automobile

headlights and the like, comprising in combination, an elongated casing provided with means for attaching it to a steering rod housing, a mounting plate of insulation within the casing, a rheostat attached to said plate and having a coil on one side and a series of contact buttons on the other side of the plate, a contact plate within the casing, and a movable contactor having an arm in continuous contact with said plate and another arm adapted to contact serially with said contact buttons. 50

2. A current regulator for automobile headlights and the like, comprising, in combination, an elongated sheet metal casing provided with means for attaching it to a steering rod housing and having a longitudinally extending slot, a mounting plate of insulation within the casing, a rheostat attached to said plate and having a coil on one side and a series of contact buttons on the other side of the plate, a contact plate attached to and insulated from said casing and provided with a slot registering with said casing slot, a movable contactor having an arm in continuous contact with said plate and another arm adapted to contact serially with said contact buttons, and an operating member attached to said contactor and extending through said slots. 55

In testimony whereof I have hereunto set my hand. 60

CHARLES F. SMITH.
